WATERTUBE BOILER

John B. Detwiler, Mimico, Ontario, Canada

Application December 2, 1941, Serial No. 421,331

5 Claims. (Cl. 122—169)

This invention relates to improvements in boilers particularly adapted for steam or hot water heating and the principal objects are to ensure the maximum transfer of heat units from the fuel to the water in the minimum of time.

A further and important object is to devise a form of boiler giving the maximum efficiency which may be manufactured at reasonable cost and will maintain its effective use for a maximum period.

The principal feature of the invention consists in the novel construction and arrangement of an auxiliary heating element within the combustion chamber of the furnace, such heating element comprising an arrangement of annular tubes having transverse circulating tubes interconnected to circulate water from the jacket of the combustion chamber progressively through the annular tubes to be super-heated and to be ultimately discharged into the upper portion of the combustion chamber jacket.

In the accompanying drawing,

Figure 1 is a longitudinal vertical sectional view through a boiler constructed in accordance with this invention.

Figure 2 is a horizontal sectional view taken through the line 2—2 of Figure 1.

Figure 3 is a part plan and part horizontal section taken on the line 3—3 of Figure 1.

Figure 4 is a vertical transverse section through a boiler taken on the line 4—4 of Figure 2.

Figure 5 is a vertical elevation in part section of the superheater showing the connection of the rings with the inlet and showing the vertical connections between the several rings.

In the manufacture of steam and water-heating boilers numerous types of superheating coils have been proposed to be placed within the main combustion chamber and the present invention has been devised with the particular purpose of achieving a much more rapid absorption of heat and circulation of the heat transfer medium than has hitherto been obtainable, with a consequent increase in efficiency and the present construction is of such a nature as to readily accommodate the variance in expansion and contraction.

In the construction herein shown the outer and inner shells 1 and 2 are spaced apart and supported upon a base 3 and are provided with the usual fire-door and smoke-flue orifices 4 and 5 respectively and a flue-cleaning orifice 6.

This shell structure may be of round, oval or rectangular construction and arranged within the interior of the combustion chamber enclosed

by the inner shell 2 is my improved form of superheater. This superheater consists of a plurality of endless annular tubes 7, 8, 9 and 10 which are spaced vertically apart, and each of these annular tubes is provided with an arrangement of a plurality of transverse cross tubes 11, 12, 13 and 14, the ends of which open into the interior of the annular tubes and are welded securely thereto.

10 The central pair of tubes 11 and 12 of the lower ring 7 are formed with openings in the bottom side centrally of their length and a large tubular member 15, which is preferably of oval shape and of a sufficient diameter to span the 15 pair of tubes, is fitted against the contour of the undersurface of these tubes surrounding the openings cut therein and is welded securely thereto.

A cross piece 16 is welded between the adjacent parallel sides of the tubes 11 and 12 and to the top edge of the tube 15 to seal the top of said inlet tube. The tube 15 is provided with an elbow 17 and a horizontal portion 18 extends through the inner shell 2 so that water from the 25 water jacket surrounding the combustion chamber may flow into the tube 15 and flowing upwardly it is directed into the two transverse tubes 11 and 12.

Water flowing in the manner described is directed in the annular tube 7 at opposite sides, consequently the direction of flow in the circular tube 7 will be as indicated by arrows in Figure 2 in an outward direction, causing it to flow around the remainder of the perimeter 35 of the tube 7 and to pass partly through the tubes 13 and 14.

The annular tube 8 spaced above the tube 7 is provided with transverse tubes similar to the tubes 11, 12, 13 and 14, and the tubes 13 and 14 and also the outward parts of the tubes 7 and 8 are connected by vertical tubes 19 and 20 so that the water flowing in through the tube 15 and carried to the ring tube 7 by means of the tubes 11 and 12, is picked up from the tubes 13 and 14 as well as from the outer portion of the ring tube and carried to the ring 8 thereabove.

The circulation in the ring 8 is reversed to that in the ring 7, and water flowing into the tubes 13 and 14 and the ends of the ring tubes 50 flows inwardly into the pair of middle tubes and it is picked up from the centre of these middle tubes by a large tubular ferrule 20' which connects with openings in the top of the central tubes and carries the water upwardly into openings in the bottom of the central tubes of

the next annular tube 9, the connections being similar to that described in connection with the connection and sealing of the large tube 15 with the tubes 11 and 12.

The water carried through the ferrule 20' to the central pair of tubes of the ring 9 flows outwardly to the perimeter and is then picked up by the vertical tubes 21 and 22 connected with the cross tubes and the outer portion of the rings and these vertical tubes conduct the water to the top ring 10 through the outer member, and the water thus fed to the top ring is circulated to the ends of the central cross tubes 23 and 24 and it flows from openings in the centre of the top side of these cross tubes and is conducted by a tubular connection 25, similar to 15, in an upward direction and discharged into the space between the crown sheets of the inner and outer jackets of the boiler.

The delivery of a superheated water or steam at the top of the crown of the combustion chamber provides a supply of hot fluid in direct alignment with the discharge opening 26 from the boiler and while this will mingle to a certain extent with the heated water or steam flowing up from the side portions of the boiler shell, it nevertheless provides a direct supply of superheated fluid.

The structure as herein described is preferably formed of steel or copper tubing with the joints in the several tubes all welded together but it will be understood that a structure similar to that shown may be made by providing cast sections and by the use of nipples and couplings a structure similar to that shown may be fabricated, and such a structure will supply the essential features of a superheater which will, because of being arranged directly in the path of the gases of combustion, absorb a maximum quantity of heat and transfer it directly to the small streams of fluid flowing through the tubular structure, and such circulation will pass the fluid through a maximum length of tubular ducts submitted directly to the applied heat.

What I claim as my invention is:

1. In a boiler, the combination with a water jacketed combustion chamber, of a plurality of horizontal annular tubular members spaced apart within said combustion chamber each having centrally arranged transverse tubes and transverse tubes arranged at either side of said central tubes, said transverse tubes having openings centrally of their length, vertical tubes connecting the central openings of the top and bottom central tubes with the water jacket, tubular means connecting the central openings of a vertically adjacent pair of central tubes arranged between said top and bottom members, and vertical tubes connecting the outer transverse tubes and rings.

2. In a boiler, the combination with a water jacketed combustion chamber, of a plurality of

annular tubes vertically spaced apart within said combustion chamber and arranged in pairs and each having centrally arranged transverse tubes and transverse tubes arranged at either side of

5 the central tubes, a tubular duct leading from the said water jacket to the central tubes of the lower annular tube, vertical tubes connecting the outer tubes of the lower and upper pairs of annular tubes, a central duct connecting the central tubes 10 of the upper of the lower pair of annular tubes and the central ducts of the lower of the upper pair of annular tubes, and a tubular duct leading from the central cross tubes of the upper annular tube.

15 3. In a boiler, the combination with a water jacketed combustion chamber, of a plurality of tubular rings horizontally arranged and spaced apart, each of said rings having a plurality of openings in the inner perimeter, transverse tubes arranged parallelly within each of said rings and having their ends fitted and welded to the inner wall of said ring around said openings, upright tubes connecting the outer rings and outer cross tubes in pairs, means connecting the adjacent central tubes of the adjacent pairs of

25 rings, means connecting the central tubes of the bottom ring with the water jacket of the boiler, said central tube connections being adapted to direct the flow of water in divided streams in opposite directions, and means connecting the central tubes of the top ring with the water jacket.

4. In a boiler the combination with a water-jacketed combustion chamber, of a plurality of vertically spaced horizontal annular tubular members each having a plurality of cross tubes opening therewith, vertical tubes connected centrally of the length of said cross tubes of alternately arranged annular members and forming circuitous passages for the flow of water, and tubes connected with the water jacket of said combustion chamber and with the upper and lower tubular members.

5. In a boiler, the combination with a water 45 jacketed combustion chamber, of a plurality of annular tubular members vertically spaced apart within said combustion chamber and each having a plurality of cross tubes the ends of which open into said annular tubes, short vertical tubular connections between cross tubes of the lowest annular tube and cross tubes of the next-adjacent annular tube thereabove, short vertical tubes connecting cross tubes of the latter annular tube with the succeeding annular tube immediately thereabove, the vertical tubes between the succeeding tubes being arranged in staggered relation, a tubular duct leading from said water jacket to the lowest tubular member, and a tubular duct leading from the centre of the top tubular member.

JOHN B. DETWILER.
